(57) **CLAIM**

The ornamental design for a rotatable casing for mobile phone as shown and described.

DESCRIPTION

FIG. 1 is a front perspective view of a rotatable casing for mobile phone according to a first embodiment of my new design.

FIG. 2 is a rear perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a front perspective view of a rotatable casing for mobile phone according to a second embodiment of my new design.

FIG. 10 is a rear perspective view thereof.

FIG. 11 is a front view thereof.

FIG. 12 is a rear view thereof.

FIG. 13 is a right side view thereof.

FIG. 14 is a left side view thereof.

FIG. 15 is a top view thereof; and,

FIG. 16 is a bottom view thereof.
